WITNESS:

UNITED STATES PATENT OFFICE.

JOHN E. CADIGAN, OF NEW YORK, N. Y.

SAFETY ATTACHMENT FOR GAS-STOVES.

1,398,888.

Specification of Letters Patent. Patented Nov. 29, 1921.

Application filed April 5, 1920. Serial No. 371,334.

To all whom it may concern:

Be it known that I, JOHN E. CADIGAN, a citizen of the United States, residing at New York, in the county of New York and State 5 of New York, have invented new and useful Improvements in Safety Attachments for Gas-Stoves, of which the following is a specification.

This invention relates to a safety attachment 10 for gas stoves, and the principal object is to provide a device which prevents accidental shutting off or turning on of gas in a gas stove.

It often happens that in moving about a 15 stove that the gas cock is opened or closed by accident from brushing the clothing against the hand lever, and the present device provides a simple and efficient means for locking the handle in any position to which it 20 may be moved.

In the accompanying drawing consisting of one sheet:—

Figure 1 is a top plan view of my improved device.

Fig. 2 is a front elevation view of the same.

Fig. 3 is a side elevation of the same, and

Figs. 4 and 5 are detail perspective views of the two attachments forming my invention.

Like reference characters refer to like parts in the several views.

Referring more particularly to the drawing, 1 represents a supply pipe from which 35 gas is fed to the stove through a valve 2 and lead 3. 4 represents the handle or lever on the valve or gas cock 2. 5 represents a collar formed to fit about a supply pipe and having an attached segmental portion 6 provided with an upstanding flange 7. The flange 7 at its upper edge is provided with 40 stiffening rib 8 as shown in Fig. 4; and is also provided with an elongated aperture 9, at the lower edge of which are formed teeth, 45 shoulders or abutments 10. A screw or bolt 11 is adapted to secure the collar 5 to the pipe 1.

12 represents a collar adapted to fit about the inner portion of the handle 4 and projecting downwardly into a pair of ears 50 through which passes a securing screw 13.

The screw 13 forms the pivot for an elongated finger 14 provided at its outer end with a knob or finger piece 15. A spring 16 is fastened between the handle 4 and the collar 5 and bears at its free end on finger 14 so as to force the same downwardly.

When the attachment is in place the finger 14 protrudes through the aperture 9 as shown in Fig. 3 and it is pressed down by 60 spring 16 into engagement with the shoulders 10. When it is desired to move the handle 4 it is necessary to raise the outer end of the finger 14 until said finger is disengaged from the shoulders 10 and is moved 65 into the upper elongated portion of the aperture 9. The handle 4 is now moved to the desired position and upon releasing the finger 14 the same is again depressed by the spring 16 into engagement with the teeth 10 70 thereby locking the handle securely against accidental displacement.

While I have described what I consider to be the best embodiment of my invention, it is obvious that many details may be varied 75 without in any way departing from the spirit of the invention and I do not wish to be considered as limited to the exact details herein described nor to anything less than the whole of my invention as herein set forth 80 and as hereinafter pointed out in the appended claim.

Having described my invention what I claim as new and desire to secure by Letters-Patent is:—

In a device of the character described, the combination of a member comprising attaching means and an upstanding flange provided with an aperture having abutment elements formed at its edge, a locking member 90 adapted to be secured to for movement with the handle of a gas cock, said locking member being adapted to extend through said aperture and to engage with said abutment elements to prevent operation of said handle, 95 one end of said locking member being formed into a handle for releasing said locking member from said abutment elements.

In testimony whereof I have affixed my signature.

JOHN E. CADIGAN.
